UNITED STATES PATENT OFFICE.

OSCAR P. TRAHERN, OF ROCKFORD, ILLINOIS.

DESIGN FOR A PUMP-WRENCH.

SPECIFICATION forming part of Design No. 27,824, dated November 9, 1897.

Application filed September 17, 1897. Serial No. 652,081. Term of patent 3½ years.

To all whom it may concern:

Be it known that I, OSCAR P. TRAHERN, a citizen of the United States, residing at Rockford, in the county of Winnebago and State 5 of Illinois, have invented and produced a new and original Design for Pump-Wrenches, of which the following is a specification, reference being had to the accompanying drawing, showing the same.

10 The accompanying drawing is an isometrical representation of my pump-wrench.

The leading feature of my design consists in the double-ended bar having openings to receive a hexagonal nut and passage-ways 15 communicating with openings.

The main bar 1 is of rectangular form in cross-section, and its ends terminate in enlargements 2, which have openings 3 of hexagonal form, one side being cut away, forming a passage-way 4 to the openings. The 20 enlarged ends are turned in opposite directions, and the openings 2 are of different sizes.

I claim as my invention—

The design for a pump-wrench herein shown and described.

OSCAR P. TRAHERN.
